UNITED STATES PATENT OFFICE.

JOSEPH LAURIN, OF MAISONNEUVE, CANADA.

SHOE-SEWING MACHINE.

SPECIFICATION forming part of Letters Patent No. 733,403, dated July 14, 1903.

Application filed October 30, 1902. Serial No. 129,491. (No model.)

To all whom it may concern:

Be it known that I, JOSEPH LAURIN, a subject of the King of Great Britain, residing at Maisonneuve, county of Hochelaga, Province 5 of Quebec, Canada, have invented certain new and useful Improvements in Outsole-Stitching Machines; and I do hereby declare that the following is a full, clear, and exact description of the invention, such as will enable others skilled in the art to which it appertains to make and use the same.

My invention relates to boot and shoe making machinery.

The object of the invention is to provide 15 very simple means for attaching an awl and a stitch-separator upon the awl-segment, whereby these two tools may operate simultaneously upon the outsole, and to provide such an arrangement as will enable the stitch-separator to be adjusted in a simple manner 20 with reference to the awl.

The invention consists in a certain combination and construction of parts to be more fully described hereinafter and definitely set 25 forth in the claims.

In the drawings, Figure 1 represents in side elevation a portion of the mechanism of an outsole-stitching machine to which my invention has been applied. Fig. 2 represents the 30 same in front elevation, a portion of the table being shown in section, together with a portion of the awl-cap. Fig. 3 represents an awl-cap in perspective. Fig. 4 represents my stitch-separator, also in perspective. Fig. 35 5 is a perspective view of a small portion of a boot, showing the outsole, together with the separator-marks and stitches.

Throughout the drawings and specification the same figures of reference refer to like 40 parts.

Referring to the parts more particularly, 1 represents the upper portion of a feed-slide. It is provided with a substantially horizontal stud 2, upon which is rotatably mounted the 45 awl-segment 3, the teeth 4 of which mesh with the teeth 5 of the awl-lever 6. To the head 7 there is pivoted at 8 the presser-foot lever 9. It is formed usually substantially as shown and carries rigidly at its extremity the 50 presser-foot 9^a, and this lever is provided with a suitable handle 10, affording means for swinging the same upwardly upon its

pivot. In proximity to the lower face 11 of the presser-foot there is mounted the table 12, which is mounted and supported upon 55 some part of the machine. (Not shown.)

Before proceeding to a further description of my invention it may be said that the parts of the mechanism which have already been described are commonly used in outsole-stitching machines, and it may be stated here that in practice the awl-segment carries the awl and rocks to and fro upon its pivot, so as to project the awl through the throat of the table and so that it passes beyond the lower 60 face of the presser-foot. In close proximity to this mechanism the needle and stitching mechanism are located, and the stitching operation progresses with the punching operation of the awl. 70

I provide an awl-cap 13, the construction of which is most clearly shown in Figs. 1 and 3. It comprises, substantially, a small flat plate, its outer edges 14 and 15 being formed in an arc to conform to the periphery of the aforesaid awl-segment 3 at its forward portion, at which point the cap is attached to the same by means of a suitable bolt 16. It should appear that the inner face 17 of this cap is provided on its inner edge with a laterally-projecting flange 18. This flange is adapted to rest against the side face of the gear-segment and is preferably of a height substantially the same as the thickness of the awl 19, which awl is clamped between the cap 85 and the face of the awl-segment, as indicated, the inner face 17 being provided with a shallow recess 20 to receive it. It should be well understood that the awl is formed into an arc having its center upon the axis of the stud 2, 90 and when the parts are in the relative positions in which they are shown in Fig. 1 the awl will have pierced the outsole, which, it should be understood, is received between the upper face of the table 12 and the lower face 95 11 of the presser-foot, the shoe being inverted during this operation.

The outer face of the awl-cap is provided with the recess or groove 21, which is curved, substantially as shown, about the axis of the 100 stud 2 as a center, its upper extremity being open, as shown. Within this recess 21 is mounted my stitch-separator 22. As indicated, this tool comprises a flat shank 23,

which is curved to conform to the shape of the aforesaid recess 21. It is formed into a head 24, having oppositely-beveled faces 25 at its extremity, meeting to form an edge 36. 5 When placed in its recess 21 in the manner shown in Fig. 1, its lower extremity lies against the tip of an adjusting-screw 26, mounted in the lower wall of the recess 21. The shank 23 is provided with a curved opening or slot 27, through which passes a clamping-bolt 28, mounted in the threaded opening 31. This construction enables the tool to be adjusted longitudinally with respect to the awl and placed in any position desired by means of this 10 clamping-bolt 28, and it may be said that the inner face of the tool normally rests against the side of the awl, as shown in the full lines in Fig. 2.

The fact that stitches of different lengths 20 are employed has led me to provide means for adjusting the separator laterally with respect to the awl. For this purpose I provide a set-screw 29, mounted in a threaded opening 30 in the shank 23. Its tip rests against the bottom of the recess 21, so that by screwing up this set-screw the head 24 of the separator may be thrown out from the awl, so that it may assume another position, such as that in which it is shown in the dotted lines in Fig. 2. 25 The table 12 is provided with a wide throat 31, through which passes the awl and the separator-tool 22.

At the left in Fig. 2 is shown a needle-arm 32, carrying the needle 33, which needle in 30 machines of this class is adapted to pass through the opening made by the awl, as will be readily understood, the feeding motion operating to bring the openings made by the awl into alignment with the needle.

40 In Fig. 5, 33^a represents the outsole of a shoe provided with stitches 34, between which are the stitch-separator marks 35, such as would be formed by the mechanism described.

45 Briefly outlining the mode of operation of the mechanism, it may be said that the awl-segment 3, which is carried upon the horizontal stud 2, mounted in the feed-slide, is rotated or rocked to and fro by means of the lever 6. The awl 19, which is carried under the cap 13, passes through the outsole while the same is held between the lower face 11 of the presser-foot 9 and the upper face of the table 12, with the shoe in an inverted position. By the side of the awl is carried the 50 stitch-separator, the edge 36 of which indents the leather of the outsole between the openings which it receives by the awl. It is longitudinally adjustable with respect to the awl by means of the adjusting-screw 26 and is clamped against the awl-cap by the screw 28. In making stitches of normal length—that is, of a length substantially equal to the width of the head 24, as viewed in Fig. 2—the side 55 of the head lies against the side of the awl, as shown. Where stitches of greater length are to be made, the set-screw 29 is screwed

up, so as to hold the head 24 in a removed position, such as that in which it is shown in the dotted lines of Fig. 2. In this manner 70 the parts are adjusted so that the indentations 35 or separator-marks will occur midway between the stitches.

While I have shown in the accompanying drawings the preferred form of my invention, it will be understood that I do not limit myself to the precise form shown, for many of the details may be changed in form or position without affecting the operativeness or utility of my invention, and I therefore reserve the right to make all such modifications as are included within the scope of the following claims or of mechanical equivalents to the structures set forth.

Having described my invention, what I consider as new, and desire to secure by Letters Patent, is—

1. In a shoe-sewing machine, the combination of an awl-carrier, an awl carried thereby, an awl-cap, a stitch-separator independent of 90 said cap and movably mounted therein, means for securing said cap to said carrier and clamping said awl therebetween, a screw mounted in the cap and passed through a slot in said separator, and independent means for longitudinally adjusting said separator, substantially as described.

2. In a shoe-sewing machine, the combination of an awl-segment pivoted to rotate about a fixed center, an awl carried thereby, a table 100 through which the awl is adapted to project, a block having a longitudinal groove in one face adapted to receive the awl, and having an arcuate groove in its opposite face, an arcuate stitch-separator having a chisel-shaped 105 edge adapted to fit in said last-named groove, means for securing said block to said segment and clamping said awl therebetween, said separator having a longitudinal slot, a screw passing through said slot and fixed in said 110 block, whereby to secure said separator in position at one side of said awl, a screw socketed in said separator and abutting against said block, whereby to adjust the distance of 115 said separator therefrom, and means for longitudinally adjusting said separator, substantially as described.

3. In combination, an awl-segment, an awl, an awl-cap having a recess on the inner face thereof adapted to receive said awl, means 120 for clamping said awl to said awl-segment, a stitch-separator carried by said awl-cap and having a slot disposed substantially in the direction of movement of said awl, a bolt passing through said slot and adapted to attach 125 said stitch-separator to said cap, and an adjusting-screw mounted in said separator the tip whereof abuts against said cap whereby said stitch-separator may be adjusted laterally.

4. In combination, an awl-segment, an awl, an awl-cap having a recess on the inner face thereof adapted to receive said awl, a bolt adapted to clamp said cap to said awl-seg-

ment, said cap having an arcuate recess in the outer face thereof, a stitch-separator mounted in said recess and having an arcuate slot therein, a clamping-bolt passing through 5 said slot adapted to clamp said stitch-separator to said cap, an adjusting-screw carried by said cap at the lower extremity of said recess and adapted to adjust said stitch-separator longitudinally in said recess; and a sec-

ond adjusting-screw adapted to adjust said separator laterally with respect to said awl.

In witness whereof I have hereunto set my hand in the presence of two witnesses.

JOSEPH LAURIN.
